UNITED STATES PATENT OFFICE.

EDWARD F. GINGRAS, OF BUFFALO, NEW YORK.

BELTING.

Application filed August 13, 1924. Serial No. 731,771.

This invention relates to an improvement in belting, and more particularly in belting of the composite type having a leather facing and a fabric backing, and in the process of 5 making the same.

My co-pending application, Serial No. 595,683, filed October 19, 1922, shows a belting of this general type, and this application discloses an improvement upon the structure 10 and shown therein the method of making the belting.

The primary object of this invention is to provide a belting capable of use under all conditions, and distinguishable over the old type 15 of belting by the fact that it can be employed in installations where a shifter is used, that is to say: where the belting is shifted transversely from one pulley to another by means 20 of an arm or shifter bearing against the edge of the belting.

Another object of this invention is to provide a belting of this type in which the leather facing projects at each side beyond the edges of the fabric backing, and the projecting 25 edges are stiffened by the application of a coating to prevent their curling under use.

A further object of this invention resides in the process of making the belting, and more particularly in the use of guides bearing 30 against the edges of the fabric backing to insure uniformity in the distance which the edges of the leather facing project beyond the edges of the fabric backing in the finished belting.

Other objects of this invention will appear 35 from the following description taken in connection with the drawings which form a part thereof, and in which

Fig. 1 is a plan view of a portion of the 40 machine on which the process of making belting which forms a part of this invention is practiced;

Fig. 2 is a transverse sectional view taken 45 along the line 2—2 of Fig. 1;

Fig. 3 is a transverse sectional view taken 50 along the line 3—3 of Fig. 1;

Fig. 4 is a somewhat diagrammatical view 55 illustrating the manner of preparing the leather facing and cotton backing before the parts are brought together; and

Fig. 5 is a cross section of belting embodying this invention, in which the outer face is given a coat of paint.

The belting which forms the subject of this 60 invention may be made by any well known process, preferably that shown in my Patent

No. 1,419,842, dated June 13, 1922. The completed belting is then led to a cutting table designated on the drawing as 10 provided with adjustable guides 11 and 12, and 60 two cutters 13 and 14, which trim the edges of the leather facing. The cutters 13 and 14 are adjustably mounted, as well as the guides 11 and 12, and their operating edges are arranged at a definite distance from the center 65 line of the belting and the side edges of the fabric belting as determined by the guides 11 and 12. The guides bear only against the fabric backing, their formation being such 70 as shown in Fig. 2 to permit the leather facing to travel beneath them without interference.

Referring to Fig. 4, it will be noted that both the leather facing 15 and the fabric backing 16 are given a coating of a suitable 75 solution, preferably glue or waterproof cement. The gum coating 17 on the leather extends to the edges of the facing, as will appear from the sectional views, Figs. 2 and 3. The coating 18 of the backing, preferably 80 extends to the edges, but does not necessarily do so, and if desired this coating may be entirely omitted, reliance being placed upon the coating 17 alone, to hold the parts in their proper relation.

Referring to Figs. 2 and 3, it will be noted 85 that the coating 17 on the facing 15 has two functions: first, it unites the fabric backing to the leather facing and second, it impregnates the edges of the facing projecting beyond the edges of the backing, and consequently when the coating is dry the leather 90 will be stiffened at the edges. This stiffening of the edges of the leather facing gives it greater strength and resistance to the curling tendency, due to the pressure of the shifter bar.

In Fig. 5 is shown a belting, the outer face 95 of which is given a coat of paint 19, which completely covers the exposed portions of 100 the fabric backing and runs down over the projecting edges of the facing. This coat of paint also stiffens the edges of the leather and under certain circumstances if desired, the gummed coating 17 beyond the edges of 105 the backing may be omitted after the belting is given a coat of paint.

While one embodiment of this invention 110 has been shown and described, applicant is not limited thereto, since it is obvious that other embodiments can be made without departing from the spirit and scope of this in-

vention as set forth in the following claim.

Having thus set forth my invention what I claim as new and for which I desire protection by Letters Patent is:

5 The process of making a belting comprising a fabric backing and a leather facing consisting in uniting the backing and facing by a gum solution with the edges of the facing projecting beyond the edges of the backing,

guiding the belting by contact with the side edges of the backing trimming the edges of the facing a pre-determined distance beyond the edges of the backing and stiffening the projecting edges of said facing.

10 In testimony whereof I have affixed my signature.

EDWARD F. GINGRAS.
